10 Claims

ABSTRACT OF THE DISCLOSURE

A system for filtering and cleaning air or gas streams, wherein an endless foraminous belt is trained over spaced-apart rollers, including a drive roller having bristle-type belt-engaging elements and is moved across the path of flow of an air or gas stream by means of a water-driven turbine having its drive shaft connected to the drive roller and having its water exhaust stream directed to effect washing of particulate matter from the belt.

BACKGROUND OF THE INVENTION

Air cleaner filter systems of the moving-belt type are commonly used in air-conditioning systems in office buildings, industrial plants and the like; and one common form of such systems employs water washing of the filter belt, either continuously or intermittently, for removing dirt, lint and other impurities which accumulate on the belt. Systems of this type conventionally require a water or other liquid supply source for cleaning the belt and an independent power source, usually electric motors, for driving the belt.

DESCRIPTION OF THE INVENTION

The present invention is directed to improvements in the moving-belt type of air filter by which the same water is employed both as the motive fluid for driving the belt and for washing the filter.

This improvement is accomplished by using a simple, low-cost, water-driven turbine, such as the type commonly employed in lawn sprinkler devices, to both drive the belt and to direct its exhaust water into washing relation with the belt.

In a preferred embodiment of this invention, an endless foraminous belt is trained over a pair of spaced-apart rollers to one of which the turbine shaft is drivingly connected, the other roller functioning as an idler roller. The exterior of the drive roller is provided with bristle-like projections which cooperate with the openings in the belt to function both as drive teeth to aid in advancing the belt and to displace particulate matter which may collect in such openings in the belt material and thereby aid the washing action of the water directed through the belt openings from the turbine exhaust.

The arrangement described thus provides an automatic self-cleaning air filter which lends itself readily to numerous applications for filtering and cleaning air, as well as other gas streams, for humidity control and for evaporative cooling.

In other modifications, the filtering and washing elements may be supplemented by drying elements employing air drawn from the cleaned air systems or from external sources to remove excess moisture from the belt before it is returned to the main circulating system.

Other and more specific objects and advantages of this invention will become more readily apparent from the following detailed description when read in conjunction with the accompanying drawing which illustrates several embodiments in accordance with this invention.

In the drawing:

FIG. 1 is a generally diagrammatic elevational view,

2

partly in section, illustrating the system in accordance with a basic embodiment of this invention;

FIGS. 2 and 3 are diagrammatic illustrations of modifications of the embodiment of FIG. 1;

5 FIG. 4 is a view generally similar to FIG. 1 to which is added a drying stage employing system air as the drying medium;

FIG. 5 is a view similar to FIG. 4 but illustrating the employment of outside air as the drying medium;

10 FIG. 6 is a view, in perspective, of the basic filter drive and wash elements of the device; and

FIG. 7 is a detail, on an enlarged scale, illustrative of the filter drive and washing elements of the apparatus.

Referring first to the structure illustrated in FIGS. 1, 15 6 and 7, the basic elements comprise an endless foraminous web or belt 10 of any suitable form to be described hereinafter, which is trained over a drive roller 11 and an idler roller 12 supported for rotation on suitable shafts or trunnions 13 and 14, respectively, the rollers being disposed on opposite sides of an air duct D through 20 which the upper and lower runs 10a and 10b, respectively, of the belt move transversely with respect to the direction of the air flow through the duct. A housing 15 mounted to opposite sides of the duct encloses the roller and the portions of the filter belt which are outside the duct. The walls of the duct are provided with suitably spaced and shaped openings 16 to permit free passage 25 of the belt runs and each of the openings is sealed about the belt surfaces by means of suitably arranged flexible sealing flaps 17 of any suitable and generally conventional form adapted to permit ready movement of the belt through the openings without substantial air leakage.

The belt is driven by means of a small water-driven turbine 18 of any well-known and generally used type such, for example, as is commonly employed for rotating 30 or oscillating lawn sprinklers. The turbine is suitably mounted in housing 15 adjacent one end of drive roller 11 and between the belt runs. The turbine is provided with a water supply conduit 19 and has the usual water-driven power shaft 20 and a water exhaust conduit 21 which is arranged to extend parallel to the drive roller and is provided with a plurality of spaced-apart discharge nozzles 22 which are disposed so as to direct water jets discharging therefrom toward the under surface of belt 35 run 10a at approximately the juncture of the upper belt run with the surface of drive roller 11, for purposes to be described more fully hereinafter.

Shaft 20 is connected by a crank 23 through a connecting rod 24 to a crank 25 mounted to shaft 13, 50 whereby rotation of shaft 20 may be transmitted to shaft 13 to rotate drive roller 11.

Belt 10 may be constructed of any suitable metallic or nonmetallic material, or combination thereof, having openings or pores of the requisite size and shape best suited for the particular service in which it is to be used. 55 For example, the belt may be constructed of perforate or woven metal, or of plastic, fibre-glass or any other suitable material having perforations or openings 30 (FIG. 7) of any suitable shape, which may be round, 60 square, elongate in the direction of the movement of the belt, and of dimensions appropriate to filter out particulate material to be removed from the air passing through the belt.

The exterior surface of drive roller 11 is provided with 65 a coating of radially projecting bristle-like elements 29 arranged and shaped to project through openings 30 in the belt. These bristle-like elements serve the dual functions of drive-teeth for transmitting the torsional force from the drive roller to the filter belt and to act as scavenging elements for displacing particulate matter, lint 70 and the like from the belt openings into the path of wash water ejecting from nozzles 22.

The bristle-like elements 29 are preferably constructed of non-metallic materials such as plastic or rubber compositions having a sufficient degree of rigidity to perform the driving and cleaning functions noted above. They may also be made of metal where the character of the filter belt and temperature conditions warrant.

In its simplest application, where only air-filtering and washing of the filter belt are required, as illustrated in FIG. 1, water under pressure will be directed through conduit 19 to turbine 18 to rotate shaft 20 which will then drive roller 11. The rotation of the latter will, through friction as well as by direct engagement of elements 29 in openings 30, drive belt 10 across the path of flow of the air stream in duct D. The water exhausting through nozzles 22 will be discharged outwardly through openings 30 to aid in cleaning the belt of any particulate matter collected therein in passage through duct D. Elements 29 will have at least initiated the dislodgment of particulate matter immediately in advance of or simultaneously with the impingement of the exhaust water on the belt openings. The combination of dislodging action of the bristle-like elements and the closely correlated washing action of the exhaust water assures effective cleaning of the portion of the belt returning to duct D as lower belt run 10a.

The exhaust wash water collecting in housing 15 after use will be discharged therefrom through a drain pipe 31.

FIG. 2 illustrates a modification where additional washing of the filter belt may be found desirable or necessary to clean the belt more effectively before it is returned to the air duct. In this case, water jets 26, of any suitable and known design (one shown) are connected to supply pipe 19 through a line 27 and have discharge nozzles 28 directed at the juncture of lower belt run 10b with idler roller 12 thus providing additional washing of the belt.

FIG. 3 illustrates a further modification designed for increasing the degree of air-cleaning and belt-washing to meet particular conditions. In this modification the filter belt 10 is passed back and forth in a plurality of passes through duct D, the several passes of the filter belt being trained over a plurality of suitably arranged idler rollers 12 before returning to drive roller 11. Only one drive turbine 18 is employed but each run of the belt as it leaves the duct is subjected to washing by a water jet 26 located adjacent the related idler roller 12.

FIGS. 4 and 5 illustrate modifications by which drying of the filter belt may be effected to regulate humidity of the filtered and washed air.

In FIG. 4 the filter belt is extended in length to form an extension 32 arranged to pass downwardly from drive roller 11 over an idler roller 33 and thence upwardly over a guide roller 34 before passing back through duct D to idler roller 12. Belt extension 32 and rollers 33 and 34 are enclosed within a housing extension 35 positioned alongside duct D and separated by means of a partition 36 from the portion of housing 15 which encloses drive roller 11 and water turbine 18, hereinafter called the washing zone, the housing extension being referred to as the drying section. The wall of duct D between belt runs 10a and 10b is provided with louver-controlled openings 37 through which filtered air after passing through upper belt run 10a is directed into housing extension 35 between the belt runs housed therein. Additional louver-controlled openings 38 in the wall of duct D below lower belt run 10b are arranged to direct filtered air passing through lower belt 10b into and through the belt extensions in housing extension 35 from which the air will exit through louvered openings 39 in the outer wall of the housing extension.

Thus, a controlled portion of the air filtered by its passage through belt runs 10a and 10b may be directed through the extended sections of the belt leaving the washing zone in order to remove wash water remaining on the belt and thereby control the humidity of the air passing through the duct after leaving the filter area.

The drying section heretofore described may be made to any suitable dimensions and with any desired number and arrangement of idler pulleys to regulate the "dwell" time of the belt under drying conditions prior to duct re-entry so as to control the moisture load in the main air stream to any extent desired.

FIG. 5 illustrates a modification of the arrangement shown in FIG. 4, differing therefrom in using outside air as the drying medium. In this modification, a blower 40 mounted in housing extension 35 draws air from outside the housing through a suction line 41 and discharges it via a discharge nozzle 42 through the portions of the belt runs passing through the housing extension between rollers 33 and 34. The drying air passing through the belt will be discharged from the housing extension through louvered openings 39.

If desired, the air going to blower 40 may be passed through a heater (not shown) if more rapid drying of the belt is desired.

It will be evident that the afore-described system lends itself readily to numerous variations in addition to those illustrated and described. The movement and washing of the belt may be continuous or intermittent. For example, an arrangement such as shown in FIGS. 4 and 5 could be timed for intermittent operation wherein one-half of the total belt length would be withdrawn from the air duct, passed through the cleaning chamber and moved into the drying chamber. Here, the cycle would be stopped and the belt held stationary until the belt was thoroughly dry and thereafter returned to the filter section and the cycle then repeated. Or, it may be found that for a specific installation only one cleaning cycle was required in a given period of time and intermittent operation could be timed accordingly.

It will be evident that numerous other alterations and modifications may be made in the details of the illustrative embodiments within the scope of the appended claims but without departing from the spirit of this invention.

What I claim and desire to secure by Letters Patent is:

1. An air filter apparatus, comprising:

- (a) an endless belt of a foraminous material movable transversely of the path of flow of an enclosed air stream;
- (b) said belt being trained over longitudinally spaced-apart drive and idler rollers;
- (c) a water-driven turbine having a driven shaft and a water exhaust conduit;
- (d) means for supplying drive water to said turbine;
- (e) means drivingly connecting said shaft to said drive roller; and
- (f) means for directing exhaust water from said water exhaust conduit into washing relation with said belt following passage thereof through said air stream.

2. An air filter apparatus according to claim 1 wherein said drive roller carries bristle-type drive elements adapted to project through openings in said foraminous material.

3. An air filter apparatus according to claim 1 wherein said last-mentioned means includes:

- (a) a header extending transversely beneath a belt run; and
- (b) a plurality of laterally spaced-apart discharge nozzles arranged on said header to direct exhaust water outwardly through the belt openings adjacent the drive roller.

4. An air filter apparatus according to claim 1 including jet means for directing wash water through a portion of said belt adjacent said idler roller.

5. An air filter apparatus according to claim 1 wherein in said endless belt is trained over a plurality of additional idler rollers arranged on opposite sides of said enclosed air stream between said drive roller and the first-mentioned idler roller, whereby to effect additional traverses of said air stream by said belt.

6. An air filter apparatus according to claim 5 including jet means for directing wash water through portions

of said belt adjacent at least some of said additional idler rollers.

7. An air filter apparatus according to claim 1 including drying means for directing a stream of drying fluid through a portion of the washed belt at a point along the path of its return to contact with said air stream. 5

8. An air filter apparatus according to claim 7 wherein said drying fluid comprises air drawn from the enclosed air stream at a point following its passage through said belt. 10

9. An air filter apparatus according to claim 7 wherein said drying fluid comprises air drawn from outside said enclosed air stream.

10. An air filter apparatus, comprising in combination with a duct enclosing the path of flow of an air stream: 15

- (a) an endless belt of a foraminous material movable through the duct transversely of the path of flow of said air stream;
- (b) said belt being trained over a drive roller and an idler roller mounted on opposite sides of said duct; 20
- (c) a housing enclosing said drive and idler rollers;
- (d) a water-driven turbine having a driven shaft and

a water exhaust conduit mounted in the housing adjacent said drive roller;

(e) means for supplying drive water to said turbine;

(f) means drivingly connecting said shaft to said drive roller;

(g) means in said housing for directing water from said water exhaust conduit into washing relation to said belt; and

(h) means for draining wash water from said housing.
